UNITED STATES PATENT OFFICE.

GEORGE M. CRAM, OF PORTLAND, MAINE.

SUBMERGED EXHAUST AND BILGE-WATER-REMOVING DEVICE FOR MOTOR-BOATS.

1,162,223.

Specification of Letters Patent. Patented Nov. 30, 1915.

Application filed January 23, 1915. Serial No. 4,053.

To all whom it may concern:

Be it known that I, GEORGE M. CRAM, a citizen of the United States, residing at Portland, in the county of Cumberland and State of Maine, have invented new and useful Improvements in Submerged Exhaust and Bilge-Water-Removing Devices for Motor-Boats, of which the following is a specification.

10 This invention relates to improvements in submerged exhaust and bilge water removing devices for motorboats, of the class set forth in the U. S. Letters Patent No. 818,951 issued to Herbert N. Goodwin, April 24, 15 1906.

The object of this invention is to provide a device which is capable of discharging the products of combustion, from the engine of the boat to which the device is attached, below the surface of the water, thus dispensing with the disagreeable odor and the noise generally associated with motor-boats and at the same time producing an exhaust which will not create back pressure 25 to the engine.

A further object of the invention is to provide means for removing bilge water or the like from the boat together with the means for automatically operating the same 30 and means for positively preventing the operation of said bilge water removing means.

The invention consists in the combination and arrangement of parts whereby the above objects and certain other objects hereinafter appearing may be attained, as set forth in the following specification and particularly pointed out in the claims.

Referring to the drawings: Figure 1 is a longitudinal section of a device embodying my invention with the same shown attached to a portion of the bottom of the boat. Fig. 2 is a section taken on line 2—2 of Fig. 1. Fig. 3 is an end view of the device as viewed from the lefthand side of Fig. 1 with the planking of the boat to which the device is attached shown in section.

Like numerals refer to like parts throughout the several views of the drawings.

In the drawings, 5 represents a portion of the planking or bottom of a vessel and 6 is a casing which is secured to said vessel, preferably by means of bolts 7 passing through a flange 8, which flange surrounds said casing.

The casing 6 embodies in its construction 55 a pressure inlet chamber or passage 10 and an outlet chamber 11, which also constitutes

a suction inlet chamber for the fluid to be acted upon. The chambers 10 and 11 are partially separated one from the other by a gradually contracted or funnel-shaped casing 12, said casing terminating in a reduced opening or discharge orifice 13 located intermediate the ends of the casing 6 and communicating with said suction chamber 11.

The chamber 10 has an inlet orifice 14 directed toward the bow of the vessel and adapted to direct a stream of fluid, preferably water which constitutes the actuating fluid, through the discharge orifice 13 into the suction chamber 11 as the boat to which the device is attached is advanced through the water. After the water has been discharged through the orifice 13 into the chamber 11 it passes from the casing 6 and through a discharge orifice 15 directed toward stern of the vessel.

The contracting walls 12 of the inlet chamber 10 greatly increase the velocity of the water passing through said casing with the result that a partial vacuum will be formed within the portion of the suction chamber 11 surrounding, or in the vicinity of said contracted portion and at this point in said casing a suction passage 16 is connected therewith through an orifice 17, said suction passage 16 being preferably formed within an upwardly extending curved portion 18, which may be connected in any suitable manner to the exhaust port of the engine.

The increased velocity of the water passing through the orifice 13 and the chamber 11 gives an additional impulse to the exhaust from the engine, which is admitted to the casing 11 through the orifice 17, and finally ejects said exhaust gases beneath the boat, resulting in an increased efficiency of the motor, due to the absence of any back pressure from the exhaust thereof.

There is considerable heat contained within the discharge from a combustion engine and as said discharge is admitted to the chamber 11, the water passing therethrough from the orifice 13 is partially heated, which consequently increases the velocity of said water and incidentally increases the suction within said chamber 11.

To take advantage of the increase in the suction within the chamber 11, due to the combining of the hot gases which are discharged from the engine and the actuating fluid passing therethrough, a second suction passage 19 is provided, which passage is

connected to said chamber 11 adjacent to the orifice 13, preferably immediately at the rear of the orifice 17 of the exhaust passage 16, said passage 19 constituting a bilge water outlet or discharge. The passage 19 is connected by a pipe 20 to the interior of said boat, thus any water which may collect in the bottom of said boat will be withdrawn therefrom by the suction created by the passage of the fluids through the casing 6.

It is not necessary that such a suction be constantly maintained. Therefore a valve 21 has been provided in the pipe 20 which may be operated at will to permit or prevent the passage of fluid therethrough. The preferred type of valve employed in this connection is the type known as the rotary valve consisting of a rotary member 22 having a passage 23 extending transversely therethrough, which may be moved to align with the passage through the pipe 20, or be arranged transversely thereof.

The rotary member 22 is arranged within a cylindrical casing 24 to which the pipe 20 is attached and a cap 25 having screw-threaded engagement with the end of said casing retains said rotary member therein. A spring 26 is preferably interposed between the end of said cap 25 and the shoulder 27 on said rotary member for the purpose of maintaining a suitable contact between the member 22 and the interior of the casing 24. The member 22 is further provided with a stem 28 projecting through the cap 25 and to which is secured an arm 29 adapted to operate said rotary member.

The valve 21, as hereinbefore stated, is for the purpose of permitting or preventing the passage of the fluid through the pipe 21 and this valve may be opened or closed when the vessel is under way or not. Should said valve be opened when said vessel is not moving and the engine is not in operation there will be no actuating fluid passing through the casing 6 to produce a suction at the mouth of the passage 19 and consequently the water will back up into said passage and if permitted so to do the boat would be flooded. To prevent this from happening a check valve 30 is arranged in the passage 19, said check valve preferably being conical and adapted to engage a conical seat 31 and thus close said passage. To guide said valve during its opening and closing movements, a stem 32 is provided, which stem extends upwardly from said valve and has sliding engagement with the valve casing 33 at 34, while a pin 35 is provided to limit the movements of said valve downwardly toward the chamber 11.

To facilitate the assembling of the device, the valve casing 33 is made separate from the casing 6, but is secured thereto preferably by screw-threads 36. The op-

eration of the check valve 30 will be automatic, that is to say, when the actuating fluid is passing through the casing 6, in the direction of the arrows "a", a suction will be produced in the exhaust passage 16, as indicated by the arrow "b" and also in the passage 19, as indicated by the arrows "c".

The valve 30 is arranged to open toward the chamber 11. Therefore should the valve 21 be opened, a suction, such as described, will draw said valve 30 inwardly until it strikes the pin 35 and retains said valve open as long as the fluid is passing in the direction of the arrows "a", or in other words, a suction is maintained at the mouth of the passage 19, but when said suction is overcome by the pressure of the water against the sides of the vessel and against said valve 30, said valve will be closed and maintained in such closed relation until the action thereagainst is reversed.

Having thus described my invention what I claim and desire by Letters Patent to secure is:

1. In combination a boat, a casing secured to the bottom of said boat, said casing embodying in its construction a passage extending longitudinally of said boat, said passage having an outlet chamber and an inlet chamber, said inlet chamber having an inlet orifice directed toward the bow of said boat and a discharge orifice substantially smaller in diameter than said inlet orifice and communicating with said outlet chamber, said outlet chamber having a suction passage connected therewith in close proximity to said discharge orifice and constituting an exhaust passage, said outlet chamber having a second suction passage adjacent to said discharge orifice, said second passage constituting a bilge water outlet, and a valve arranged in said second passage adapted to be operated to permit or prevent the passage of fluid through said second passage.

2. In combination a boat, a casing secured to the bottom of said boat, said casing embodying in its construction a passage extending longitudinally of said boat, said passage having an outlet chamber and an inlet chamber, said inlet chamber having an inlet orifice directed toward the bow of said boat and a discharge orifice substantially smaller in diameter than said inlet orifice and communicating with said outlet chamber, said outlet chamber having a suction passage connected therewith in close proximity to said discharge orifice and constituting an exhaust passage, said outlet chamber having a second suction passage adjacent to said discharge orifice and at the rear of said exhaust passage, said second passage constituting a bilge water outlet, and a valve arranged in said second passage adapted to be operated to permit or

prevent the passage of fluid through said second passage.

3. In combination a boat, an engine arranged within said boat, a casing adapted to be fastened to the bottom of said boat, said casing embodying in its construction a passage extending longitudinally thereof for the actuating fluid, said passage being contracted intermediate its ends, said casing 10 also having a bilge water suction passage connected therewith adjacent to said contracted portion, a valve adapted to close said suction passage, an exhaust pipe connecting said engine with said casing in close

proximity to said contracted portion con- 15 structed and arranged to unite the exhaust gases from said engine with the actuating fluid passing through said casing, said ex- haust and said actuating fluid combining to create a suction through said bilge water 20 suction passage.

In testimony whereof I have hereunto set my hand in presence of two subscribing witnesses.

GEORGE M. CRAM.
